UNITED STATES PATENT OFFICE.

JOSEPH E. BOHNER, OF ANSONIA, CONNECTICUT.

DESIGN FOR A LAMP-FOUNT HOLDER.

SPECIFICATION forming part of Design No. 24,451, dated July 2, 1895.

Application filed May 11, 1895. Serial No. 549,012. Term of patent 3½ years.

To all whom it may concern:

Be it known that I, JOSEPH E. BOHNER, a citizen of the United States, residing at Ansonia, in the county of New Haven and State of Connecticut, have invented and produced a new and useful Design for Lamp-Fount Holders, of which the following is a full and complete specification, reference being had to the accompanying drawing, which illustrates the design.

In the drawing the figure represents a side view of a lamp-fount holder, illustrating my design.

The design consists of a lamp-fount holder of the general outline shown and bearing at regular intervals the conventionalized anthe-

mion figures A, surrounded by the empire wreath B. Between the wreaths are located the flambeaux C. Around the top of the holder is the border of segmental plackets D. Variously dispersed between these figures of design are other minor designs, as shown.

The essential features of the design are those above indicated.

What is claimed as new is—

The design for lamp fount holders and similar articles, substantially as shown and described.

JOSEPH E. BOHNER.
